UNITED STATES PATENT OFFICE.

LEON JEANNOTTE, OF GRAVELBOURG, SASKATCHEWAN, CANADA.

SINGLETREE CONSTRUCTION.

Application filed December 28, 1921. Serial No. 525,525.

To all whom it may concern:

Be it known that I, LEON JEANNOTTE, a citizen of the Dominion of Canada, residing at Gravelbourg, in the county of Moose Jaw,

5 Province of Saskatchewan, have invented certain new and useful Improvements in Singletree Constructions, of which the following is a specification.

The present invention appertains to improvements in draft rigging and particularly relates to the singletree construction. The principal object of the invention is to provide an easy and durable means for securing the traces of the harness to the singletree.

With this and other objects in view the invention consists in the construction, combination and arrangement of parts as will be hereinafter fully described, illustrated in the accompanying drawings and pointed out in the claim hereunto appended.

In the drawings:

Figure 1 is a perspective view illustrating my present invention.

25 Fig. 2 is a fragmentary elevation illustrating the attachment of the trace with the outer terminal of the singletree.

Referring to the drawings like characters of reference designate like parts in the drawings.

30 Referring now particularly to Figure 2, at the outer terminals of the singletree 3 is mounted the bracket 6 which is provided with an inwardly offset terminal 7. The numeral 8 indicates a spring member which is substantially mounted on the edge of the singletree 3 and the outer terminal thereof 9 fits over the bracket 6. The spring 8 is tensioned outwardly by the resilience of the 35 metal of which it is formed and by means of the auxiliary compression springs 9^a which are housed in a suitable casing 10. The upper terminal of the compression spring 9^a is seated in a suitable casing indicated by the numeral 11. The outer terminal of the casing 11 bears against the 40 spring 8. The numeral 12 indicates an abut-

ment or retainer carried by the spring 8 and abuts against the terminal 7. Referring particularly to Figure 1 the numeral 3 indicates the singletree which is pivotally mounted as at 4 in the yoke 5.

50 In operation, when it is desired to attach a tracing of the harness worn by a draft animal, the spring 8 is sprung inwardly until a sufficient space is left intermediate the abutment 12 and the terminal 7 to allow the entrance of the link 13 of the chain 14, which is connected to the tracing 15. When the link 13 engages with the terminal 7 the spring 8 springs backwardly into position. It will be readily apparent 55 that disengagement of the link 13 is prevented.

55 While it is believed from the foregoing description that the nature and advantages of my invention will be readily apparent I desire to have it understood that the same is merely illustrative of the preferred embodiment of my invention to which I do not limit myself and that a deviation from such details may be resorted to as do not form a departure from the spirit of the invention as defined by the appended claim.

60 70 What I claim as new is:

A singletree having brackets mounted on the outer terminals thereof, the outer terminals of the said brackets extending inwardly, springs mounted on the said singletree, the outer terminals of the said springs embracing the said brackets, auxiliary compression springs adapted to tension the said springs outwardly, abutments carried by the said springs and adapted to keep the said springs in spaced relation from the inwardly extending terminals of the said brackets and retain trace connections when attached to 75 said terminals.

80 85 90 In testimony whereof, I hereunto affix my signature in the presence of two witnesses.

LEON JEANNOTTE.

Witnesses:

HUGH PICK,
C. R. WALMESLEY.
